(Cl. D55—1)

To all whom it may concern:

Be it known that I, Robert C. Koslo, a citizen
of the United States, residing at Parma, in the
county of Cuyahoga and State of Ohio, have in-
vented a new, original, and ornamental Design
for a Garbage Grinder, of which the following is a
specification, reference being had to the accom-
panying drawing, forming a part thereof, in
which:

Fig. 1 is a side elevation showing my new
garbage grinder design;

Fig. 2 is a front elevation; and

Fig. 3 is a top plan view thereof.

I claim:

The ornamental design for a garbage grinder,
substantially as shown.

ROBERT C. KOSLO.
